FRAME FOR A COMBINED TABLE AND SEAT UNIT

William S. Berry, P.O. Box 205, Anchorage, Ky.

Filed Oct. 6, 1961, Ser. No. 66,997

Term of patent 14 years

(Cl. D33—14)

The single figure is a perspective view of a frame for a combined table and seat unit, showing my new design.

The characteristic features of my design for the combined table and seat unit reside in a pair of doubled frame members of the configuration shown, each pair interconnected at the bottom by a pair of short transverse bars under the seat supports and the table supports interconnected by inverted U-shaped brackets at the inner bights of the paired supports, all as shown.

I claim:

The ornamental design for a frame for a combined table and seat unit, as shown and described.
